Primary Examiner — Patricia A Palasik(74) *Attorney, Agent, or Firm* — Adam Warwick Bell(57) **CLAIM**

The ornamental design for a transfer robot, as shown and described.

DESCRIPTION

FIG. 1 is a perspective view of the invention (a transfer robot) viewing it in profile, diagonally and from the side, generally from above and from the front side.

FIG. 2 is a perspective view of the invention viewing it in profile, diagonally from the side, generally from above and from the rear side.

FIG. 3 is a front elevation view of the invention.

FIG. 4 is a rear elevation view of the invention.

FIG. 5 is a left side elevation view of the invention; and,

FIG. 6 is a top plan view of the invention.
